SEPARABLE CONNECTOR FOR FLAT MULTIPLE-CONDUCTOR CABLES

Judson C. Cole and James R. Hall, Sidney, N.Y., assignors to The Bendix Corporation, Sidney, N.Y., a corporation of Delaware

Filed Nov. 4, 1960, Ser. No. 67,275
7 Claims. (Cl. 339—176)

This invention relates to a separable electrical connector and in the embodiment thereof illustrated herein particularly relates to a separable connector for cables in flattened, tape form.

The invention has among its objects the provision of a novel separable connector for multiple-conductor cables.

A further object of the invention is the provision of an improved separable electrical connector which may be used to advantage with multiple-conductor cables of the flat or tape type.

Yet another object of the invention lies in the provision of a separable connector of the type indicated, such connector being characterized by the positiveness of electrical connection between mating contact portions of the connector.

Still a further object of the invention lies in the provision of a separable electrical connector which is particularly adapted for use with a rigid circuit element such as a board containing a printed circuit.

A still further object of the invention lies in the provision of a separable electrical connector which is rugged and compact, wherein the mating contacts make secure electrical contact with each other despite long use under rigorous conditions and despite repeated engagement of the connector parts with each other and repeated disengagement of such parts, and which does not add appreciably to the weight of an assembly with which it is used.

The above and further objects and novel features of the invention will more fully appear from the following description when the same is read in connection with the accompanying drawings. It is to be expressly understood, however, that the drawings are for the purpose of illustration only and are not intended as a definition of the limits of the invention.

In the drawings, wherein like reference characters refer to like parts throughout the several views,

FIG. 1 is a view in longitudinal section of a first connector part in accordance with the invention, such first connector part being adapted to receive an element such as a printed circuit board and to provide for electrical connection to a second connector part;

FIG. 2 is a view in front end elevation of the connector part shown in FIG. 1;

FIG. 3 is a view in longitudinal section of a second part of a separable electrical connector, such second part being adapted to interfit with the first connector part shown in FIGS. 1 and 2;

FIG. 4 is a view in front end elevation of the second connector part;

FIG. 5 is a view in longitudinal section through an assembly of the first and second connector parts positioned in operative mating relationship, a printed circuit board being shown operatively engaged in the first connector part and such assembly;

FIG. 6 is an exploded fragmentary view in perspective of the assembly of FIG. 5;

FIG. 7 is a view in longitudinal section through an alternative single-ended connector part in accordance with the invention; and

FIG. 8 is a view in longitudinal section through a second alternative double-ended connector part made in accordance with the invention.

2

In the embodiments shown in the drawings, the separable connector of the invention is shown employed with a multiple conductor cable of the flattened or tape type. Whereas the connector of the invention displays perhaps its maximum advantages when used with such type of cable, it is to be understood that the connector of the invention may also be used advantageously with cables of other types.

In FIG. 1 there is shown a first connector part, generally designated 10, which is designed for use with an assembly such as that shown in FIG. 5. In such assembly the rear (right hand) end of connector part 10 matingly interfits with a second connector part 11 to which is connected a flattened multiple conductor cable 13. Connector part 10 is shown mounted upon and extending through a panel 12, which may be the wall of a circuit-containing enclosure. The forward (left hand) end of connector part 10 is shown in the assembly as receiving and making electrical contact with a flat circuit element such as a printed circuit board 14.

Turning now to FIGS. 1 and 2, it will be seen that the first connector part 10 has an outer shell or housing 15 having a forward end portion 16 of larger transverse dimensions and a smaller rear portion 17. Portions 16 and 17 of the shell are connected by a smoothly curved necked-in portion 19. A flange 20 is connected to shell portion 16 adjacent the rear end thereof so that the shell can be attached to a partition 12 in the manner shown in FIG. 5.

30 A rubber or rubber-like electrically insulating insert 21 fits snugly within the shell 15 so as to form a seal therewith. Insert 21 is accurately positioned within and retained from withdrawal from the shell by having an outwardly projecting boss 24 on the forward portion 22 of the insert interfitting within a hole 25 in the forward end of the shell. The insert is further retained within the shell by a second boss 27 on the rear insert portion 26, boss 27 projecting outwardly within a hole 29 in the rear end of the shell. When the insert is so held, the intermediate curved portion 30 thereof snugly engages the inner surface of the curved portion 19 of the shell.

The forward portion 22 of insert 21 has a longitudinally extending opening 31 therein, opening 31 being designed to receive a portion of printed circuit board 14 and also to position upper and lower contact fingers 35 and 36 making electrical contact with the various contacts on element 14. The rear portion 26 of the insert has a laterally elongated recess or pocket 32, such recess containing a plurality of laterally spaced contact fingers 34, each of which is integral with one of contact fingers 35 and 36, as the case may be. Opening 31, in the embodiment shown, has a height, that is, a dimension transverse to its length and lying in the plane of the paper in FIG. 1, which is markedly greater than that of recess 32.

55 The spring contact fingers 34 are integral with the respective upper and lower spring fingers 35 and 36. Such integral contacts are in the form of flat wires made, for example, of beryllium-copper alloy, and are retained in an electrically insulating block 37 made, for example, of plastic material which extends from side to side of connector part 10. The conductor wires may be molded in place within mounting block 37 and may have a short bent portion 39 lying within the block in order to retain the conductor more securely therewithin. Block 37 is mounted within a seat 38 in insulating insert or sheath 21, being snapped therewith before the sheath is inserted in shell 15. A vertically extending partition 43 in sheath 21 forms one end of seat 38; portion 34 of the conductor extends through and snugly interfits with an opening through partition 43 as shown.

The forward portion 22 of the sheath 21 is provided

with a plurality of laterally spaced longitudinally extending grooves 42, 44 on the inner wall thereof. As shown in FIG. 2, upper grooves 42 and lower grooves 44 are laterally spaced. The forward ends of the conductors 32, 35 project through an opening at the forward end of seat 38 and then extend angularly upwardly in a run 40. Forwardly of run 40 the conductor extends longitudinally of connector part 10 for a substantial distance along the bottom of groove 42, following which it is bent downwardly at a relatively shallow angle to form the forward, active portions 35 of the contacts. The extreme forward ends of contacts 35 are bent upwardly and then rearwardly so that preferably, when in the relaxed condition shown in FIG. 1, at least the upper ends of such upwardly and rearwardly bent portions of contacts 35 lie within the grooves 42. The portions of the conductors forming the lower contacts 36 are similarly bent, but in reverse directions from those of the upper contacts. Thus upon leaving the seat 38 the forward ends of the conductors forming the lower contacts are bent downwardly angularly in runs 41, from which the conductors lie along the bottoms of grooves 44 for an appreciable distance. Forwardly of such straight portions the conductors are bent shallowly angularly upwardly to form the active contact portions 36, the forward ends of such contacts being bent downwardly and then rearwardly so that at least a portion of each of the forward ends of the lower conductors lie within grooves 44.

Contacts 35 and 36 cooperate with a circuit element such as a printed circuit board 14 in the manner more clearly shown in FIG. 5. Board 14 has a body 45 made, for example, of reinforced electrically insulating plastic material. The body 45 has a thickness which closely conforms to the vertical dimension of the recess 31 in the forward end of insulating sheath 21, so that the body 45 may be snugly received within such recess. Body 45 has a plurality of laterally spaced upper and lower bared contact ribbons or contacts 46 and 49, respectively, thereon, the upper and lower contacts alternating in a lateral direction so as to overlie and make contact with the upper and lower contact fingers 35 and 36. The contacts 46 and 49 are in the form of electrically conducting strips, such strips being secured to body 45 as by being adhesively bonded thereto. Strips 46 and 49 lead to various circuit elements (not shown) included on the circuit board 14. The rear edge of the circuit board shown has a portion 51 of reduced width which conforms to the width of recess 31 in connector part 10 so that portion 51 may be received an appreciable distance within recess 31 as shown.

Connector part 11, designed for cooperation with the rear end portion of the above described connector part 10, is shown more particularly in FIGS. 3 and 4. As there shown, connector part 11 has an outer shell or housing 52, which may be made, for example, of metal. In the embodiment shown shell 52 is made in two parts, there being a first, forward portion 54 and a second, rear portion 55, the two parts being telescoped and secured together as by welding. Within the rear portion of shell 52 there is positioned a rubber-like electrically insulating insert or sheath 56 which has snug, sealing engagement therewith. A strong rigid electrically insulating insert 57 is positioned within sheath 56, the rear end of the insert having compressive engagement with the inner upper and lower walls of sheath 56. The forward end of the recess within sheath 56 has upper and lower flared or tapered zones 59 which are adapted sealingly to engage the end portion 66 of the sheath which projects rearwardly of the shell of connector part 10.

The insert 57 is of such length that its forward end lies somewhat rearwardly of the forward end of shell portion 54. The upper and lower inner walls of shell portion 54 are spaced somewhat from insert 57 to provide recesses 60 which receive the rear end of the shell of connector part 10. The upper and lower surfaces of insert 57 are

provided with alternating grooves, the grooves in the upper surface of the insert, shown at 61, sloping forwardly and downwardly from an intermediate zone of the insert, and the grooves on the lower surface of the insert, not specifically shown, slanting forwardly and upwardly. A conductor tape or foil, shown at 62 in FIG. 3, is secured to the bottom of the groove 61; a tape or foil is similarly secured to the bottom of each of the grooves in the lower surface of the insert. The forward ends 64 of the grooves in the upper surface of the insert lie adjacent the lower forward edge of the insert, and the forward ends of the grooves in the lower surface of the insert lie adjacent the upper forward corners of the insert. The described construction of the insert and of the upper and lower grooves therein provide a plurality of vertically extending partitions, one between each pair of the grooves.

The multiple conductor cable, generally designated 13, has a plurality of thin, ribbon-like conductor strips which are sealed in spaced parallel relationship between upper and lower insulating layers to form an insulating body. Such cable may be, for example, one manufactured by the Tape Cable Company, Rochester, New York; a typical one of such cables employs conductors made of thin copper strips and a body made of clear, transparent thermoplastic material such as a polyester resin.

As shown in FIG. 3, the insulation is removed from the forward edge of the cable 13 and alternate bared conductors of the cable are bent upwardly and downwardly to overlie the rear edge of the respective conductor strips or foils on insert 57. The conductors may be secured as by soldering to such conductor strips to form joints of which one is shown at 65.

The described connector parts 10 and 11 are shown in their assembled condition in FIG. 5. As there shown, the rear end of connector part 10 is telescoped within the forward end of connector part 11, the rear end 66 of the sheath of connector part 10 snugly and sealingly fitting within the forward flared portion 59 of sheath 56. A peripherally extending bead 67 is preferably divided on sheath portion 66, such bead being deformed upon assembly, as shown, whereby to insure the formation of a seal between sheaths 66 and 56. When connector portions 10 and 11 are telescopically engaged, the rear ends of spring contact fingers 34 initially enter freely within the upper and lower grooves on insert 57, since the forward ends of such grooves lie well beyond the vertical center of the insert and thus of the relaxed position of fingers 34. When, however, parts 10 and 11 are advanced toward fully mating position, the forward ends of contact fingers 34 engage the contact strips on the bottoms of the grooves in insert 57, and are progressively flexed either upwardly or downwardly from their relaxed positions, whereby to make secure electrical contact with the conductor strips. To insure that parts 10 and 11 will remain in fully engaged position, there is provided a flange 69 on the forward end of shell 54 and there is provided a similar flange 70 on the rear end of shell portion 17 of connector part 10. Such flanges at least substantially abut when the connector parts are fully engaged, and may be held in such condition by bolts, not shown, extending through holes in the two flanges.

To insure that the connector parts may be assembled only in the correct position, there are provided orienting formations on the shells of the respective connector parts. In the embodiment shown, such formations take the form of a projection 71 in the forward end of shell 54, a slot 72 (FIG. 1) on the bottom rear end of the shell of connector part 10, two upper projections 74 on shell 54 and two slots 75 on the rear end of shell 17 of connector part 10.

In FIG. 7 an alternative connector part made in accordance with the invention is shown. Such connector part, there designated by the character 80, may be employed to cooperate and interfit with the connector part 11 shown in FIG. 3.

In FIG. 7 a multi-conductor flattened cable 79 is shown connected to the contacts of connector part 80. The connector part has a strong rigid shell 81 having an outwardly directed flange 82 thereupon for cooperation, for example, with a flange such as shown at 69 in FIG. 3. Connector part 80 has a rubber-like electrically insulating sheath 84 snugly and sealingly engaged therewithin, such sheath having an elongated recess within the rear end thereof. Rearwardly directed contact fingers, of which one is shown at 85, extend rearwardly within such recess. The forward ends of the contact fingers are secured within a strong rigid electrically insulating insert 86 as by being molded therewithin. Preferably the portion of the conductor finger within the insert block is diverted as shown to provide a strong mechanical connection therewith. In the embodiment shown, the diversion of the contact fingers is such as to expose alternate fingers on the upper and lower surfaces of the insert block, respectively, whereby to permit connection between the conductors of the cable and the contact fingers as by soldered joints, of which one at the upper surface of the insert is shown at 83, and another of which, shown at the lower surface of the insert, is designated 86'.

In FIG. 8 there is shown a further alternative connector part 89 in accordance with the invention. Connector part 89, which is double-ended, may, for example, be employed with two connector parts such as that shown at 11 in FIG. 3.

Connector part 89 has a strong rigid shell 90 within which is securely and sealingly fitted a rubber-like electrically insulating sheath 91. A strong rigid electrically insulating insert 92 is snugly engaged within a seat in sheath 91, preferably being snapped therein before assembly of the sheath within the shell. An integral conductor 94, made of springy metal such as beryllium-copper, has its central portion mounted within insert block 92 and its opposite, contact finger-forming end portions 95 and 96 projecting longitudinally within elongated recesses at the opposite ends of the sheath 91. Shell 90 carries two peripherally extending flanges 97, 99 which are adapted to interact with flanges such as that shown at 69 in FIG. 3, whereby to retain two connector parts 11 in operative engagement with the opposite ends of connector part 89.

Although only a limited number of embodiments of the invention have been illustrated in the accompanying drawings and described in the foregoing specification, it is to be especially understood that various changes, such as in the relative dimensions of the parts, materials used, and the like, as well as the suggested manner of use of the apparatus of the invention, may be made therein without departing from the spirit and scope of the invention as will now be apparent to those skilled in the art.

What is claimed is:

1. A separable electrical connector comprising an elongated electrically insulating sheath, an electrically insulating insert block positioned in the sheath intermediate the ends of the sheath, the sheath presenting open ended recesses having two opposite broad walls receiving contacts of other connector parts on opposite sides of the block, a first one of said recesses having a markedly greater height than the second recess, and an elongated spring member affixed intermediate its length to the block generally centrally of the thickness of the latter, opposite ends of the spring member projecting into the respective recesses in the sheath and forming contact fingers for engagement by said contacts of said other connector parts, the contact finger in a first recess being bent to lie with its outer end lying nearer one broad wall of the recess than the other, the contact finger in the second recess lying generally axially of such second recess.

2. A separable electrical connector comprising a first connector part having an elongated electrically insulating resilient sheath, a rigid shell intimately surrounding and confining the sheath, means retaining the sheath within

the shell, an electrically insulating elongated insert block positioned in the sheath intermediate the ends of the sheath, the sheath presenting elongated open ended recesses on opposite sides of the block, a plurality of spaced elongated parallel spring members affixed intermediate their ends to the block, opposite ends of the spring members projecting into the respective recesses in the sheath and forming contact fingers, the fingers in one recess lying with the outer free ends thereof disposed adjacent a plane equidistant from the opposite walls of said one recess, and a second connector part adapted to be received within said one recess of the first connector part, said second connector part comprising an insulating board having a forward edge portion adapted to be received within the said one recess of the first connector part, and a plurality of longitudinally extending spaced parallel conductors on the board adapted to make electrical contact with the contact fingers in the said one recess of the first connector part, there being inclined staggered grooves in the opposite faces of the forward edge of the board, the spaced parallel conductors being disposed at the bottoms of the grooves in the board, the grooves being of such widths as to receive the contact fingers located in said one recess of the first connector part when the forward edge portion of the board is mounted in said one recess.

3. An electrical connector as defined in claim 2 wherein the contact fingers in the other of said recesses in the first connector part lie with the outer free ends of successive fingers disposed adjacent the opposite walls of said other recess, comprising a third connector part comprising an insulating plate having a forward edge portion adapted to be received within said other recess of the first connector part, and a plurality of longitudinally extending spaced parallel conductive strips on opposite faces of said plate adapted to make electrical contact with the contact fingers in said other recess of the first connector part, the conductive strips on one said face being in staggered relation to the said conductive strips on the other said face, whereby the said strips on opposite faces of the plate make contact with alternate contact fingers in said other recess when the forward edge portion of the plate is mounted in said other recess.

4. A separable electrical connector comprising an elongated electrically insulating sheath, an electrically insulating insert block positioned in the sheath intermediate the ends of the sheath, the sheath presenting open ended recesses having two opposite broad walls receiving contacts of other connector parts on opposite sides of the block, and an elongated spring member affixed intermediate its length to the block generally centrally of the thickness of the latter, opposite ends of the spring member projecting into the respective recesses in the sheath and forming contact fingers for engagement by said contacts of said other connector parts, the contact finger in a first recess being bent to lie with its outer end lying nearer one broad wall of the recess than the others, the contact finger in the second recess lying generally axially of such second recess.

5. A separable electrical connector comprising an elongated electrically insulating sheath of extended width, an electrically insulating insert block of extended width positioned in the sheath intermediate the ends of the sheath, the sheath presenting open ended laterally elongated recesses having two opposite broad parallel walls receiving contacts of other connector parts on opposite sides of the block, a first one of said recesses having a markedly greater height than the second recess, a plurality of spaced parallel elongated spring members affixed intermediate their length to the block generally centrally of the thickness of the latter, opposite ends of the spring members projecting into the respective recesses in the sheath and forming contact fingers for engagement by said contacts of said other connector parts, the contact fingers in the first recess being bent to lie with their outer ends lying nearer one broad wall of the recess than the other, the

contact fingers in the second recess lying generally axially of such second recess.

6. A separable electrical connector as claimed in claim 5, wherein the inner surfaces of the opposite broad walls of the first recess have longitudinally extending parallel grooves therein, the grooves in the opposite walls being disposed in staggered relationship, and a substantial portion of the length of each of the contact fingers in the first recess lies within its respective groove.

7. A separable electrical connector comprising a first connector part having an elongated electrically insulating resilient sheath, a rigid shell intimately surrounding and confining the sheath, means retaining the sheath within the shell, an electrically insulating elongated insert block positioned in the sheath intermediate the ends of the sheath, the sheath presenting elongated open ended recesses on opposite sides of the block, a plurality of spaced elongated parallel spring members affixed intermediate their ends to the block, opposite ends of the spring members projecting into the respective recesses in the sheath and forming contact fingers, the fingers in one recess lying with the outer free ends of successive fingers disposed adjacent the opposite walls of said recess, and a second connector part adapted to be received within said one recess of the first connector part, said second connector part comprising a 15 plate-like insulating board having a forward edge portion

5

tion adapted to be received within the said one recess of the first connector part, and a plurality of longitudinally extending spaced parallel conductors on opposite faces of the board adapted to make electrical contact with the contact fingers in the said one recess of the first connector part, the said conductors on one said face being in staggered relation to the said conductors on the other said face, whereby said conductors on opposite faces of said board engage alternate contact fingers in said one recess when the forward edge portion of the board is mounted in said one recess.
